UNITED STATES PATENT OFFICE

139,252

DESIGN FOR A MANUAL AND MOTOR DRIVING UNIT WITH REMOTE POSITION INDICATOR

William P. Lear, North Hollywood, Calif., assignor, by mesne assignments, to Reconstruction Finance Corporation, Cleveland, Ohio, a corporation of the United States

Application September 27, 1943, Serial No. 111,221

Term of patent 14 years

(Cl. D26—5)

To all whom it may concern:

Be it known that I, William P. Lear, a citizen of the United States of America, residing at North Hollywood, in the county of Los Angeles, in the State of California, have invented a new, original, and ornamental Design for a Manual and Motor Driving Unit With Remote Position Indicator, of which the following is a specification, reference being had to the accompanying drawings, forming a part thereof.

In the drawings:

Fig. 1 is a front elevational view of a manual and motor driving unit with remote position indicator embodying my present design.

Fig. 2 is a left-hand elevational view of the unit illustrated in Fig. 1.

Fig. 3 is a top plan view of the unit illustrated in Fig. 1.

Fig. 4 is a right-hand elevational view of the unit illustrated in Fig. 1.

Fig. 5 is a rear elevational view of the unit illustrated in Fig. 1.

I claim:

The ornamental design for a manual and motor driving unit with remote position indicator, substantially as shown.

WILLIAM P. LEAR.
